SWITCH

Filed May 29, 1931

Inventor

By Charonor O'Brien Attorney

UNITED STATES PATENT OFFICE

DAVE HANSON, OF McCALLSBURG, IOWA

SWITCH

Application filed May 29, 1931. Serial No. 540,980.

This invention relates to new and useful improvements in circuit makers and breakers, and more particularly to a novel switch unit capable of being used in conventional screw type electrical receptacles.

The principal object of this invention is to provide a switch of the character mentioned wherein the parts are detachably connected to permit ready disassembly to permit repair or replacement of parts in a quick and efficient manner.

Another important object of the invention is to provide a switch of the character mentioned provided with a threaded base portion capable of disposition for operation in conventional electrical receptacles of the screw type.

Other important objects and advantages of the invention will become apparent to the reader of the following specification.

In the drawing:—

Figure 1 represents a front elevational view of the switch connected to a conventional receptacle.

Fig. 2 represents a side elevational view of the switch unit.

Fig. 3 represents a front end elevational view of the shell of the switch.

Fig. 4 represents a longitudinal enlarged sectional view through the switch unit shown in Fig. 2.

Fig. 5 represents a cross sectional view of the assembled switch taken substantially on line 5—5 of Fig. 4.

Referring to the drawing wherein like numerals designate like parts, it can be seen that numeral 5 refers to the wall plate of an electrical receptacle of the threaded type. This receptacle is of conventional make, and forms no part of the present invention. The present invention involves only the switch unit which is clearly shown in Fig. 2.

In carrying out the present invention, a shell 6 is provided externally with a jacket 7 shaped to provide threads for cooperation with the threads of a conventional threaded type electric receptacle. This shell 6 is of di-electric material and hollow, and is provided at one end with a centrally projecting protuberance 8 having a threaded bore 9 ex-

tending therethrough, to receive the threaded shank 10 of the central contact 11 which is provided with a screw driver block 12.

The opposite open end of the shell 6 is provided with a circumferentially extending shoulder having corrugations 13 on the periphery thereof. Extending into the shell from the jacket 7 is the conductor strip 14 which connects to a semi-circular band 15 on the internal shoulders of the shell.

For disposition into the shell, a metallic barrel 17 is provided and its closed end 18 is provided with a threaded opening to receive the inner end of the contact shank 10, as in the manner shown in Fig. 4. An annulus 19 circumscribes the opposite end of the barrel 17 and is suitably secured thereto. The inner side of this annulus 19 carries a circular contact strip 20 from which a connector 21 extends. This connector is provided with an opening therein to receive the set screw 21a which is disposed into the di-electric bushing 22. This bushing is located within an opening 23 in the barrel 17 intermediate the ends thereof and opens into the circumferentially extending groove 24 on the inner side of the barrel. The inner end of this set screw 21a is exposed on the surface of the inner recessed end of the bushing 22.

Rotatably mounted in the barrel 17 is the cylindrical body 25 of some suitable conductive material. This body 25 is provided with a transversely extending bore 26, in each end of which a ball contact 27 is mounted.

Interposed between the balls is a compressible spring 28 which normally serves to project the balls outwardly into the aforementioned groove 24 on the inner side of the barrel 17. As is clearly shown in Fig. 5, the barrel 17 at the groove 24 is provided at 90° intervals with recesses 29 in which the balls 27 can seat.

The outer end of the body 25 is provided with a threaded reduced extension 30 for engagement into the metallic bushing 31 of the di-electric knob 32.

It can now be observed, that when the knob 32 is rotated to position wherein one of the set screws 21a is engaged by one of the balls 27, connection will be established between

the bracket 7 and the contact 11, by way of the connection 14, strip 16, band 20, connection 21, screw 21a, ball 27, and shell 17 into which the shank 10 of the contact 11 is 5 threaded.

While the foregoing specification sets forth the invention in specific terms, it is to be understood that numerous changes in the shape, size and materials may be resorted to 10 without departing from the spirit and scope of the invention as claimed hereinafter.

Having thus described my invention, what I claim as new is:—

1. A switch of the character described comprising a body of insulating material provided with a threaded jacket thereon, a contact on one end of the body, rotary means in the body connecting or disconnecting the contact with respect to the jacket, said rotary 15

means comprising a barrel in the body having a circumferentially extending groove on its inner side, a rotary plug in the barrel, a contact on the rotary plug, a contact on the barrel, and a connection between the last- 20

25 mentioned contact and the said jacket, said barrel and plug being of current conductive material and a connection between the contact on the body and the said barrel.

2. A switch of the character described comprising a di-electric body provided with a threaded shell, a contact at one end of the body, spaced from the shell, a rotor in the body provided with a knob at its outer end, said contact being connected to the rotor, 30

35 and contactor means between the rotor and the shell, said contactor means comprising a transverse bore through the rotor, a contact connected to the shell, and a spring projected contact member in the bore engageable 40 with the contact of the shell.

3. A plug switch of the character described comprising a hollow di-electric body, a contact at one end of the body, a conductor barrel in the body, said contact being provided with a threaded shank engageable into the barrel, a rotor rotatably mounted in the barrel, interlocking means between the rotor and the barrel, and contact means between the rotor and the shell. 45

50 In testimony whereof I affix my signature.
DAVE HANSON.
